ROTARY SWITCH STATOR BODY

Kenneth C. Allison, 1546 South Shore Drive,
Crystal Lake, Ill. 60014

Filed Mar. 22, 1968, Ser. No. 11,089

Term of patent 14 years

Int. Cl. D13—03

U.S. Cl. D26—13

FIG. 1 is a top perspective view of a rotary switch stator body showing my new design.

FIG. 2 is an enlarged bottom plan view thereof.

FIG. 3 is a side elevational view thereof.

FIG. 4 is a side elevational view showing the stator body as it appears when viewed from a horizontally turned position at 90 degrees variance to its position as shown in FIG. 3.

I claim:

The ornamental design for a rotary switch stator body, as shown and described.
